UNITED STATES PATENT OFFICE.

HARRY W. SMITH, OF WORCESTER, MASSACHUSETTS.

DESIGN FOR WOVEN FABRIC.

SPECIFICATION forming part of Design No. 26,045, dated September 15, 1896.

Application filed July 31, 1896. Serial No. 601,249. Term of patent 14 years.

To all whom it may concern:

Be it known that I, HARRY W. SMITH, a citizen of the United States, residing at Worcester, in the county of Worcester and Commonwealth of Massachusetts, have invented and produced a new and original Design for Woven Fabrics, of which the following is a specification.

In the drawings, Figure 1 is a face view of a section of fabric embodying my design. Fig. 2 is an enlarged view of a smaller section of the fabric.

The design consists of a series of heavy members 1, composed of a plurality of woof-threads, and between them a series of lighter members 2, also composed of a plurality of woof-threads.

The warp-threads are arranged in pairs 3 across the face of the fabric, thus forming alternate spaces 4 of substantially the same width, the intermediate space 5 being of a different width.

What I claim is—

The design for woven fabrics herein shown, consisting of heavy, horizontal members and intermediate lighter members with vertical members of uniform size and so arranged that the alternate spaces between the vertical members shall be of the same width and the intermediate space of a different width.

HARRY W. SMITH.
